DESIGN FOR A GUARDED FINGER RING

Julius Braun, Union, N. J., assignor to Abelson & Braun, Newark, N. J., a corporation of New Jersey

Application April 24, 1936, Serial No. 62,288

Term of patent 7 years

To all whom it may concern:

Be it known that I, Julius Braun, a citizen of the United States and a resident of Union, in the county of Union and State of New Jersey, have invented a new, original, and ornamental Design for a Guarded Finger Ring, of which the following is a specification, reference being had to the accompanying drawing, forming part thereof.

I claim:

The ornamental design for a guarded finger ring, as shown,

JULIUS BRAUN.
